UNITED STATES PATENT OFFICE.

JOHN FOUNTAIN, JR., OF ELIZABETH, NEW JERSEY.

JUNCTION OR OUTLET BOX.

No. 907,139.

Specification of Letters Patent.

Patented Dec. 22, 1908.

Application filed October 31, 1907. Serial No. 400,103.

To all whom it may concern:

Be it known that I, JOHN FOUNTAIN, Jr., a citizen of the United States, residing at Elizabeth, in the county of Union and State 5 of New Jersey, have invented certain new and useful Improvements in Junction or Outlet Boxes; and I do hereby declare the following to be a full, clear, and exact description of the invention, such as will enable 10 others skilled in the art to which it appertains to make and use the same, reference being had to the accompanying drawings, and to letters of reference marked thereon, which form a part of this specification.

15 My invention relates to improvements in junction or outlet boxes to be used in buildings, and designed for making connections in the electrical wiring of buildings.

My invention has for its object the novel 20 construction of an outlet box, comprising a cast metal frame provided with wrought metal sides, an opening or openings in each of said sides, the openings in the wrought metal sides being filled in one case with cast 25 metal disks and in the other with wrought metal washers and with cast metal disks, said disks being integral with the frame and cast in said openings simultaneously with the casting of the frame, as distinguished 30 from boxes heretofore placed on the market in which the disks were made of wrought metal and either forced back in position in the side by means of a press or cast over said disks during the process of casting the box.

35 In the drawings which accompany this specification, Figure 1 shows a plan view of my improved box, the cover of which has been removed. Fig. 2 shows a side elevation of the box complete. Fig. 3 shows a 40 side elevation in section of my improved box, taken on line *a*—*b* of Fig. 1. Fig. 4 shows a fragmentary sectional plan view of my improved box, taken on line *x*—*x* of Fig. 2. Fig. 5 shows a side elevation of a modified 45 form of a wrought metal side or blank used in my improved box. Fig. 6 shows a plan view of a modified form of my improved box, the cover of which has been removed. Fig. 7 shows a side elevation of the box complete. 50 Fig. 8 shows a side elevation in section of the modified form of my improved box, taken on line *a*—*b* of Fig. 6, and Fig. 9 shows a side elevation of a wrought metal side or blank

used in the modified form of my improved box.

55 Similar letters of reference are employed in all of the said above described views to indicate corresponding parts.

In the said drawings, *a* indicates the complete outlet box, which consists essentially of 60 a skeleton frame comprising the base *b* and the corner posts *c*. These posts *c* are provided with screw holes *d* for securing upon the said posts *c* by means of the screws *e* the top cover *f*. Each corner *c* is provided 65 with grooves *g* for the reception of the ends of the plates *h*. These plates *h* are preferably made of wrought metal and provided with openings, preferably circular in shape, stamped out in any well known manner. 70 The base *b* is provided with the usual screw holes *b'* for securing the complete box in position to any part of the building.

j are runners formed on the base *b*, which register with the openings *i* of the wrought 75 metal plates *h*, and the primary object of the runner *j* is to conduct the molten metal to the openings *i* in the said plates *h* during the process of casting the base *b* of the outlet box, thereby filling the openings *i* with cast 80 metal disks *i'*, which disks, when the box is cast, form integral parts of the box, in view of the fact that said disks *i'* are cast in the openings *i*, simultaneously with the frame or base *b*. It will be seen that any one of the 85 cast metal disks *i'* can be readily removed from the opening *i* in the side of the box by the workman at the desired point by striking the cast metal disk *i'* a blow with a hammer or similar tool, thereby breaking away the 90 disk *i'* and that part of the runner *j* which projects over the circular opening in back of the plate *h*.

The pattern employed in the casting of 95 my outlet box is almost identical in appearance with the box represented in Fig. 1, with the exception that side plates having no openings are used in the pattern during the molding operation.

The manner of arranging the plates *h*, 100 which are provided with the openings *i*, in the sand so as to cast the disk *i'* in said opening *i*, as well as the corner posts *c* securely around the end edges of the plates *h* will be readily understood, and need not be described here.

In Fig. 5, I have shown the plate *h* provided with notches *k* formed in the ends of said plate into which the molten metal will also run during the process of casting, thereby forming an additional positive lock which will prevent accidental disengagement of the plates *h* from the corner posts *c*.

In Figs. 6, 7, 8 and 9, the wrought metal side plate *h* is provided with openings *i*. Secured in the openings *i* of the wrought metal side plate *h* and held therein by friction are the wrought metal washers *i*². The runners *j* formed on the base of the box illustrated in Figs. 6, 7 and 8 are extended to register with the openings *i*³ of the wrought metal washers *i*², and in this particular case, conduct the molten cast metal to the openings *i*³ in the wrought metal washers *i*² to form the cast disks, which disks, when the box is fast, form integral parts of the box.

It will be seen that in the modified form above described, any one of the cast metal disks can be readily removed from the wrought metal washers *i*² in the side of the box, by striking the cast metal disk a blow with a hammer, thereby breaking the same away from the wrought metal washer, and providing an opening smaller in diameter than the openings in the box shown in Figs. 4 to 5. Should it be desired for obvious reasons to produce a larger opening, it will only be necessary to remove the wrought metal washers *i*² by giving the same a blow with a hammer or similar tool.

I am fully aware that boxes are made with varying numbers of closing disks made of the same material as the sides which are secured in the openings of said sides and held therein by friction or by means of small tangs and the like; but I am not aware that the openings in the side plate of the box have ever been filled with cast metal, said cast metal being integral with and cast in said opening simultaneously with the box, capable of being broken away to form an opening or openings in the box for the reception and the direct attachment thereto of the gas or electric fixtures employed in the construction of buildings.

I claim:

1. A junction or outlet box comprising a cast metal frame provided with wrought metal sides, each side having an opening therein, said opening being filled with cast metal disks, said disks being cast integral with the frame.

2. A junction or outlet box comprising a cast metal frame provided with wrought metal sides, each side having a series of openings therein, said openings being filled with cast metal disks, said disks being cast integral with the frame.

3. A junction or outlet box comprising a cast metal frame provided with wrought

metal sides, the ends of the sides having notches formed therein, each side having an opening therein, said opening being filled with cast metal disks, said disks being cast integral with the frame.

4. A junction or outlet box comprising a cast metal frame provided with wrought metal sides, each side having an opening therein, said opening being filled with cast metal disks, said disks being cast integral with the frame and cast in said openings simultaneously with the frame.

5. A junction or outlet box comprising a cast metal frame provided with wrought metal sides, each side having an opening therein, runners formed integral with the said frame and communicating with the openings in said sides, said openings being filled with cast metal which is cast simultaneously with the frame and forms an integral portion of said frame and runner.

6. A junction or outlet box comprising a cast metal frame provided with wrought metal sides, each side having an opening therein, the ends of the sides having notches formed therein, runners formed integral with the said frame and communicating with the openings in said sides, said openings being filled with cast metal which is cast simultaneously with the frame and forms an integral portion of said frame and runner.

7. A junction or outlet box comprising a cast metal frame provided with wrought metal sides, each side having a series of openings therein, the ends of the sides having notches formed therein, runners formed integral with the said frame and communicating with the openings in said sides, said openings being filled with cast metal which is cast simultaneously with the frame and forms an integral portion of said frame and runner.

8. A junction or outlet box, comprising a cast metal frame provided with wrought metal sides, each side having an opening therein, a washer secured in said opening, said washer being filled with cast metal disks, said disks being cast integral with the frame.

9. A junction or outlet box, comprising a cast metal frame provided with wrought metal sides, each side having a series of openings therein, washers secured in said openings, said washers being filled with cast metal disks, said disks being cast integral with the frame.

10. A junction or outlet box, comprising a cast metal frame provided with wrought metal sides, the ends of the sides having notches formed therein, each side having an opening therein, washers secured in said openings, said washers being filled with cast metal disks, said disks being cast integral with the frame.

11. A junction or outlet box, comprising a

cast metal frame provided with wrought metal sides, each side having an opening therein, washers secured in said openings, said washers being filled with cast metal disks, said disks being cast integral with the frame and cast in said washers simultaneously with the frame.

12. A junction or outlet box comprising a cast metal frame provided with wrought metal sides, each side having an opening therein, washers secured in said openings, runners formed integral with the said frame and communicating with the washers in said sides, said washers being filled with cast metal which is cast simultaneously with the frame and forms an integral portion of said frame and runner.

13. A junction or outlet box, comprising a cast metal frame provided with wrought metal sides, each side having an opening therein, the ends of the sides having notches formed therein, washers secured in said openings, runners formed integral with the

said frame and communicating with the washers in said sides, said washers being 25 filled with cast metal which is cast simultaneously with the frame and forms an integral portion of said frame and runner.

14. A junction or outlet box comprising a cast metal frame provided with wrought 30 metal sides, each side having a series of openings therein, the ends of the sides having notches formed therein, washers secured in said openings, runners formed integral with the said frame and communicating with the 35 washers in said sides, said washers being filled with cast metal which is cast simultaneously with the frame and forms an integral portion of said frame and runner.

This specification signed and witnessed 40 this 28th day of October 1907.
